UNITED STATES PATENT OFFICE.

WILLIAM M. GUNLOCK, OF CHICAGO, ILLINOIS, ASSIGNOR TO DRYDEN RUBBER COMPANY, OF CHICAGO, ILLINOIS, A CORPORATION OF ILLINOIS.

DESIGN FOR A RUBBER SOLE.

Application filed February 6, 1924. Serial No. 8,541. Term of patent 3½ years.

To all whom it may concern:

Be it known that I, WILLIAM M. GUNLOCK, a citizen of the United States, residing at Chicago, in the county of Cook and State of Illinois, have invented a new, original, and ornamental Design for a Rubber Sole, of which the following is a specification.

In the accompanying drawing forming part of this specification—

Figure 1 is a bottom view;
Figure 2 is an edge view; and
Figure 3 is a view as seen from the left of Figure 1, of the new design for rubber soles.

I claim:
The ornamental design for a rubber sole as shown.

WILLIAM M. GUNLOCK.
